[57] ABSTRACT

A frequency synthesizing system includes frequency synthesizing means operative to produce an adjustable intermediate frequency, frequency dividing means for dividing the intermediate frequency by an adjustable division factor to produce an output frequency, setting means operable to set up the desired value of the output frequency, and control means automatically responsive to the setting means to adjust the synthesizing means and the dividing means in dependence on the desired value of the output frequency, such that the value of the intermediate frequency produced by the synthesizing means produces, when divided by the division factor of the dividing means, the desired output frequency.

FIG. 5.

FREQUENCY SYNTHESIZING SYSTEM

The invention relates to frequency synthesizers.

According to the invention, there is provided a frequency synthesizing system, including frequency synthesizing means operative to produce an adjustable intermediate frequency, frequency dividing means connected to divide the intermediate frequency by an adjustable division factor to produce an output frequency, setting means operable to set up the desired value of the output frequency, and control means automatically responsive to the setting means to adjust the synthesizing means and the dividing means such that the value of intermediate frequency produced by the synthesizing means produces, when divided by the division factor of the dividing means, the desired output frequency.

According to the invention, there is also provided a method of frequency synthesis, in which an intermediate frequency is synthesized and then divided to produce the desired output frequency, the division factor being automatically selected according to a predetermined program relating values of division factors to values of the desired output frequency, and the intermediate frequency being automatically selected according to the product of the division factor and the third output frequency, such that the intermediate frequency, when divided by the division factor, gives the desired output frequency.

A frequency synthesizing system embodying the invention, and a method of frequency synthesis according to the invention, will now be described, by way of example only, and with reference to the accompanying drawings in which:

FIG. 1 is a block circuit diagram of the system;

FIGS. 2, 3 and 4 are more detailed block circuit diagrams of various parts of the system of FIG. 1; and

FIG. 5 shows waveforms occurring in the system.

In broad outline, the synthesizer system comprises frequency synthesizing blocks 10, 12, 14 and 16 which are settable by an operator in a manner to be described to produce an output frequency F_1 on a line 18. The frequency F_1 is fed through an automatically variable frequency divider 20 to produce the required synthesized frequency F_o on an output line 22. The divider 20 comprises, in this example, two frequency dividing chains in series, the first dividing chain dividing by 10^m and the second frequency dividing chain dividing by 2^n , where m can be 0, 1 or 2, and n can be 0, 1, 2 or 3. The total division factor of the divider 10 is therefore $Q = 10^m \cdot 2^n$. The synthesizer system has a control panel 24 with, in this example, five manually operable controls 24A to 24E which are used by the operator to set up the required decade digits of the frequency F_o to be synthesized. In the particular example of the synthesizer to be described, the frequency range covered is 0 to 160 MHz (actually 0.1 to 159.99 MHz). The controls 24A to 24D each have 10 settings, "0" to "9," and respectively set up the number of tens of KHz in the required output frequency, the number of hundreds of KHz, the number of units of MHz, and the number of tens of MHz. The control 24E sets the number of hundreds of MHz in the required output frequency, and thus has two settings of "1" and "0." The control panel 24 controls an indices selector 26 which, for each desired frequency value set up on the control panel 24, selects particular values of m and n (that is, it selects a

particular total division factor Q for the divider 20). In addition, the control unit 24 (in combination with the indices selector 26) sets up a multiplier unit 28. The multiplier unit 28 is connected to control the synthesizer blocks 10 to 16 such that the value of the frequency F_1 on line 18 is, when divided by the division factor Q of the divider 20, equal to the desired value of the output frequency F_o .

The synthesizer system will now be described in more specific detail.

In a manner to be explained, the synthesizer blocks 10, 12 and 14 can be set so that the frequency F_1 on line 18 is variable between 80 and 160 MHz (actually 80 and 159.99 MHz), that is, variable over one octave. F_1 can therefore be represented by

$$F_1 = 80 + 10A + B + C/10 + D/100 \quad (\text{in MHz}) \quad (1)$$

20 As Q the total division factor of the divider 20, then

$$F_o = F_1/Q. \quad (2)$$

Q is variable from 1 (when m and n are both zero) and 800 (when m is 2 and n is 3), thus making F_o variable between 0.1 MHz and 159.99 MHz.

25 The synthesizer block 10 synthesizes the digit D (see equation 1). It is connected to receive a fixed frequency Fr on a line 40 which, in this example, is 0.6 MHz, and a variable frequency, F_D , on a line 42. The line 42 is connected to a switch 44 which has 10 settings, numbered 0, 1, 2, ..., 9. The 10 input terminals of the switch 44 are respectively connected to receive inputs of different frequency. Thus, when the switch is in setting 0, an input frequency of 5.4 MHz is connected to line 42, and the input frequency increases by 0.1 MHz per switch setting, up to 6.3 for setting 9. The illustration of switch 44 is purely diagrammatic, and in a practical case the switch would be electronic in nature. 30 As shown, it is controlled by a logic unit 46 which is connected by a channel 48 to the multiplier unit 28. The channel 48 has four lines which carry, in binary coded decimal (BCD) form, signals representing that setting of switch 44 which, as determined by the multiplier 28, is required in order to produce the correct value of the digit D in the frequency F_1 on line 18. If the multiplier 28 determines that the required value of D is 2, say, then it produces, in BCD form, a signal representing decimal 2 on channel 48 and switch 44 is set into setting 2 by the logic unit 46 thus giving F_D a value of 5.6 MHz; and similarly for the other values of D . It will be seen that the different possible values of F_D (5.4 to 6.3 MHz) are such that

$$F_D = 5.4 + D/10 \quad (3)$$

35 The synthesizer block 10 can have any suitable form, as described in more detail hereinafter, but is such as to produce an output frequency F_2 on a line 43 where

$$F_2 = Fr + F_D = 0.6 + F_D. \quad (4)$$

40 From equation (3) above, it therefore follows that

$$F_2 = 6 + D/10 \quad (5)$$

45 The output frequency F_2 is divided by 10 in a fixed divider 50 which therefore produces an output frequency of F_3 where

$$F_3 = 0.6 + D/100 \quad (6)$$

The frequency F_3 is one input to the synthesizer block 12 which is similar in construction and operation to the synthesizer block 10, and receives a second input, F_C , on a line 52. It produces an output F_4 on a line 53 where

$$F_4 = F_3 + F_C \quad (7)$$

The line 52 is connected to a 10-setting switch 54 which is similar in construction and operation to the switch 44 and has 10 settings 0, 1, 2, ..., 9 in which it respectively applies frequencies of 5.4, 5.5, 5.6, ..., 6.3 MHz to line 52. Switch 54 is connected to be controlled by a logic unit 56 which is connected by a channel 58 to the multiplier 28. The channel 58 has four lines which carry, in BCD form, the required value of the digit C as determined by the multiplier 28. Thus, for example, if the multiplier 28 determines that the desired value of the digit C is 6, then it produces, in BCD form, a signal on channel 58 representing decimal 6 and the logic unit 56 is caused to set the switch 54 into setting 6, thus giving F_C , a value of 6.0 MHz; and correspondingly for the other values of C.

It will be seen that the different possible values of F_C (5.4 to 6.3 MHz) are such that

$$F_C = 5.4 + C/10 \quad (8)$$

From equations (6), (7) and (8), it follows that

$$F_4 = 6 + C/10 + D/100 \quad (9)$$

The synthesizer block 14 is similar in construction and operation to the synthesizer block 10 and 12. It receives an input frequency F_A on a line 60 and second input frequency F_B , on an input line 62, and produces an output frequency F_5 on a line 64 where

$$F_5 = F_A + F_B \quad (10)$$

The frequency F_B is controlled by a switch 66 which has 10 settings, 0, 1, 2, ..., 9. The 10 inputs of the switch 66 are respectively connected to receive fixed frequencies of 4, 5, 6, ..., 188.13 MHz. Switch 66 (which, like the switches 44 and 54, is shown only diagrammatically) is controlled by a logic unit 68 which is connected by a channel 70 to the multiplier 28. Channel 70 has four lines which carry, in BCD form, the required value of the digit B as determined by the multiplier 28. If the multiplier 28 determines that the required value of B is 6, then a signal representing decimal 6 is produced in BCD form on channel 70 and the logic unit 68 is caused to set switch 66 into setting 6 to give F_B a value of 10 MHz; and correspondingly for the other values of B. Therefore

$$F_B = 4 + B \quad (11)$$

The frequency F_A is controlled by a switch 72 which has eight settings, 0, 1, 2, ..., 7. The eight inputs of the switch 72 are respectively connected to receive frequencies of 70, 80, ..., 140 MHz. Switch 72 (which, like the other switches, is shown only diagrammatically) is controlled by a logic unit 74 which is connected by a channel 76 to the multiplier 28. The logic unit 74 responds to the signal received on channel 76 by producing an output indicating the desired value of the digit A and setting the switch 72 accordingly. Thus if the desired value of A is 6, then the switch 72 is set into setting 6; and so on. It will be seen that the range of possible values for F_A is such that

$$F_4 = 70 + 10A \quad (12)$$

The logic unit 74 differs from the other logic units 46, 56 and 68 in that the switch setting which it produces is not numerically equal to the decimal value of the signal received via channel 76. The reason for this is explained later. Table I below indicates the switch setting produced by the logic unit 74 for each signal value on channel 76.

TABLE I

Required value of Digit A	Decimal value of signal in channel 76	Output of Logic Unit 74 and corresponding setting of switch 72	
		0	1
0	8	0	0
1	9	1	1
2	0	2	2
3	1	3	3
4	2	4	4
5	3	5	5
6	4	6	6
7	5	7	7

From equations (10), (11) and (12), it will be seen that

$$F_5 = 74 + 10A + B \quad (13)$$

The synthesizer block 16 receives the two frequencies F_4 and F_5 and, being similar in construction and operation to the other synthesizer blocks, produces the output frequency F_1 where

$$F_1 = F_5 + F_6 \quad (14)$$

From equations (9), (13) and (14), it will be seen that

$$F_1 = 80 + 10A + B + C/10 + D/100$$

as required.

As explained, the indices selector 26 is connected to the control panel 24 by five channels 90, 92, 94, 96, 98. Each of channels 90 to 96 has four lines which carry, in BCD form, signals representing the setting of the controls 24A to 24D. Channel 98 has only one line which carries a binary "0" or a binary "1" dependent on whether control 24E is set to 0 or 1. The indices selector 26 has an output channel 100 having seven lines which can respectively carry the binary signals $m_0, m_1, m_2, n_0, n_1, n_2, n_3$. The selector 26 responds to the signals received on the channels 92 to 98 by determining the required value of Q , the division factor of divider 20 ($Q = 10^m \cdot 2^n$) and determines the coding of the seven lines of channel 100 accordingly. Thus, for example, if the selector 26 determines that the required value of Q is 8, then the required values of m and n are 0 and 3, and it sets lines m^0 and n^3 to binary "1" and the remaining five lines in channel 100 to binary "0," and similarly for the other values of m and n .

Table II below shows the values of Q and F_0 (in MHz) for different values of m and n , having regard to the fact that F_1 is variable between 80 and 160 (actually 159.99) MHz.

TABLE II

	$n = 0$	$n = 1$	$n = 2$	$n = 3$
$m = 0$	$Q = 1$ to 159.99	$Q = 2$ to 79.99	$Q = 4$ to 39.99	$Q = 8$ to 19.99
	$F_0 = 80$	$F_0 = 40$	$F_0 = 20$	$F_0 = 10$
$m = 1$	$Q = 10$ $F_0 = 8$	$Q = 20$ $F_0 = 4$	$Q = 40$ $F_0 = 2$	$Q = 80$ $F_0 = 1$

The serial BCD multiplier unit 136 (see FIG. 4) comprises four AND gates 148 to 151, all of which are connected to receive the clock signals on the line 134 and which have their second inputs respectively connected to receive the signals P2 to P5. The outputs of the AND gates 148 to 151 are respectively connected to the inputs of scale of ten cascaded decimal counters 153 to 156. The outputs of the counters are respectively connected to BCD encoders 158 to 164. The latter respectively feed the channels 48, 58, 70 and 76.

Each signal P2 opens the gate 148. Clock pulses from line 134 therefore pass through the gate 148, and are counted up by the counter 153. The number of clock pulses passing into the counter during each pulse of the signal P2 is proportional to the length of that pulse, and thus directly proportional to the BCD value presented on channel 90. In other words, the number of pulses counted by counter 153 during each pulse of signal P2 is equal to the product of the decimal value set up by the control 24A and the division factor, Q, selected by the indices selector 26.

A pulse of signal P3 now arrives and opens gate 149. The number of clock pulses on line 134 which are counted by the counter 154 is therefore equal to the product of the setting of control 24B and the division factor Q. In similar fashion, pulses P4 and P5 open gates 150 and 151 and cause the counters 155 and 156 to count the products of Q and the settings of the controls 24C and 24D. Since the counters are cascaded, their outputs continuously carry, in decimal form, the last four digits of the product of Q and the number set up by the controls 24A to 24D. The BCD encoders 158 to 164 convert the decimal signals into BCD form and respectively energize the channels 48, 58, 70 and 76. The counters are reset during each pulse ϕ_1 by means of a line 165, while the encoders are updated during each pulse ϕ_1 (but before the counters are reset) by means of a line 166.

It will be observed that the product produced by the multiplier 28 is not directly affected by the setting of the control 24E. However, the product produced is indirectly affected by the setting of the control 24E since the latter affects the value of the division factor Q which in turn affects the value of the product produced by the multiplier 28.

It will also be noted that the output of the multiplier 28 does not indicate the value of the most significant digit of the required value of F_1 . However, since F_1 cannot be more than 159.99 MHz, this digit can only be decimal "1" or "0." Furthermore, F_1 cannot be less than 80 MHz. Therefore, when the decimal value of the digit presented on channel 76 is 8 or 9, the most significant digit of F_1 must be zero, and when the decimal value of the digit on channel 76 has the value of 0, 1, 2, 3, 4 or 5 (it cannot have the value of 6 or 7), the most significant digit of F_1 must be 1. Thus, the output from the multiplier 28 implicitly indicates the value of the most significant digit of F_1 .

The decimal value of the output on channel 76 represents, therefore, the number of tens of MHz in the required value of F_1 . This number must lie within the range 8 to 15 (since the minimum value of F_1 is 80 MHz and the maximum is 159.99 MHz). If the required number of tens of MHz is 8 or 9, this is indicated directly by the decimal value of the output in channel

76; if the number of tens is 10, 11, 12, 13, 14 or 15, this is indicated in channel 76 by the number 0, 1, 2, 3, 4 or 5, respectively. Since the synthesizing system inherently provides a minimum value for F_1 of 80 MHz, it follows that the value of A (see equation 1) must be 8 less than the number of tens indicated by the decimal value of the output on channel 76. This is taken care of by the logic unit 74 in the manner explained above with reference to Table I.

10 The operation of the complete synthesizer will now be considered using a specific numerical example.

Let it be assumed that the required output frequency, F_0 is 29.43. Thus, the controls 24A to 24E would respectively be set to decimal values of 3, 4, 9, 2 and 0 and BCD coded versions of these decimal values would be presented to the indices selector 26 on the channels 90 to 98. In addition, the BCD values of the settings of controls 24A to 24D would be presented on channels 90 to 96 to the multiplier 28.

In the manner explained above, and as shown by Tables II and III, the indices selector 26 would determine that the required value for m is 0 and for n is 2, that is, $Q = 4$. Therefore, the indices selector 26 would produce a binary "1" on the lines m_0 and n_2 in the channel 100, thus enabling the AND gates 102 and 124 (FIG. 2) of the divider 20, the other lines of the channel 100 being maintained at binary "0."

30 In the manner explained, the multiplier unit 28 multiplies the decimal value of the total signal presented to it on channels 90 to 96 by the division factor Q. The resultant product is 117.72, of which, as explained above, only the last four digits appear on the output channels 48, 58, 70 and 76. Thus, channel 48 carries decimal 2, channel 58 carries decimal 7, channel 70 carries decimal 7, and channel 76 carries decimal 1, these numbers of course being presented in BCD form.

35 Therefore, the logic unit 46 sets the switch 44 (FIG. 1) into setting 2, thus giving frequency F_D a value of 5.6MHz. Therefore, from equations (4) and (5), F_2 is 6.2MHz, and F_3 is 0.62MHz.

Similarly, logic unit 56 sets the switch 54 into setting 7, thus giving F_c a value of 6.1MHz. Therefore, from equation (7), F_4 becomes 6.72 MHz.

40 The logic unit 68 determines that the required value of B is 7, and sets the switch 66 into the setting 7, thus giving the signal F_B a value of 11MHz. The logic unit 74 determines from the signal on channel 76 (decimal 1) that the required value of A is 3 (see Table I) and sets the switch 72 into the setting 3, thus giving the signal F_A a value of 100MHz. Therefore, from equation (10) it follows that the synthesizer block 14 produces an output frequency, F_5 , of 111MHz.

45 55 From equation (14), it follows that the output frequency F_1 produced on line 18 is given by

$$F_1 = 6.72 + 111 \text{ MHz}$$

$$= 117.72 \text{ MHz}$$

60 65 Therefore, the output frequency F_0 produced on line 22 is given by $F_0/Q = 117.72/4 = 29.43$, as required.

From the above, it will be seen that the synthesizer system described enables the synthesis of output frequencies in a large frequency range (0 to 160MHz, more than 1 octave), and yet avoids the use of very high frequencies with the attendant difficulties of

$m = 2$	to 9.99*	to 7.99	to 3.99	to 1.99
	$Q = 100$	$Q = 200$	$Q = 400$	$Q = 800$

$Fo = 0.8$	$Fo = 0.4$	$Fo = 0.2$	$Fo = 0.1$
to 0.99*	to 0.79	to 0.39	to 0.19

The values marked * should theoretically be 15.99 and 1.59 but the system is arranged to limit these values to the figures given so as to avoid overlap between the range of outputs obtainable when $m = 0$ and $n = 3$ and the range obtainable when $m = 1$ and $n = 0$, and to avoid overlap between the range obtainable when $m = 1$ and $n = 3$ and the range obtainable when $m = 2$ and $n = 0$.

If the decimal values of the digits of Fo respectively set up by the controls 24E to 24A are given by K_1, K_2, K_3, K_4, K_5 , respectively, then Table III below shows the logic required to produce the signals $m_0, m_1, m_2, n_0, n_1, n_2, n_3$. In column 3 of the Table, the decimal numbers in brackets indicate the decimal values of the digits K_1 to K_5 . In a manner which will be clear to those skilled in the art, the indices selector 26 contains logic required to satisfy Table III and to produce the required values of signals m_0 to n_3 for each required value of Fo .

TABLE III

Function to be Realized	Truth Statement for the Function	Gating Function
m_0	If K_1 is 1 or K_2 is 1-9 (i.e. 10-159.99 MHz)	$K_1(1) + K_2(1-9)$
m_1	If K_1 is 0, and K_2 is 0, and K_3 is 1-9 (i.e. 1-9.99 MHz)	$K_1(0).K_2(0).K_3(1-9)$
m_2	If K_1 is 0, and K_2 is 0, and K_3 is 0, and K_4 is 1-9 (i.e. 0.1-0.99 MHz)	$K_1(0).K_2(0).K_3(0).K_4(AU-9)$ (Alternatively $\bar{m}_0, \bar{m}_1$)
n_0	and K_2 is 8-9; or If m_1 , and K_2 is 1; or if m_0 , and K_3 is 8-9; or If m_2 , and K_3 is 1; or if m_0 , and K_4 is 8-9	$m_0 [K_1(1) + K_2(8-9)] +$ $m_1 [K_2(1) + K_3(8-9)] +$ $m_2 [K_3(1) + K_4(8-9)] +$
n_1	If m_0 , and K_2 is 4-7; or If m_1 , and K_3 is 4-7; or If m_2 , and K_4 is 4-7	$m_0 [K_2(4-7)] +$ $m_1 [K_3(4-7)] +$ $m_2 [K_4(4-7)] +$
n_2	If m_0 , and K_2 is 2-3; or If m_1 , and K_3 is 2-3; or If m_2 , and K_4 is 2-3	$m_0 [K_2(2-3)] +$ $m_1 [K_3(2-3)] +$ $m_2 [K_4(2-3)] +$
n_3	If m_0 , and K_2 is 1; or If m_1 and K_3 is 1; or If m_2 , and K_4 is 1	$m_0 [K_2(1)] +$ $m_1 [K_3(1)] +$ $m_2 [K_4(1)] +$ (Alternatively, $\bar{n}_0 \bar{n}_1 \bar{n}_2$)

FIG. 2 illustrates the divider 20. It comprises three two-input AND gates 102, 104, and 106 which are respectively connected to be enabled by the signals m_0, m_1 , and m_2 . Gate 102 has its second input connected directly to line 18 (FIG. 1). Gate 104 has its second input connected to line 18 through a frequency divider 108 having a fixed division factor of 10, while the second input of gate 106 is connected to line 18 through frequency divider 110 which also has a fixed division factor of 10. The outputs of the gates 102 to 106 are connected through an OR gate 112 to a chain of three binary dividers or flip-flops 114, 116, 118. The output of the OR gate 112 is connected to one input of a two-input

AND gate 120, while the outputs of the flip-flops 114 to 118 are respectively connected to one input of further two-input AND gates 122, 124, 126. The second input of each of the AND gates 120 to 126 is respectively connected to receive the signals n_0, n_1, n_2, n_3 . The outputs of the AND gates 120 to 126 are connected to the line 22 (FIG. 1) through an OR gate 128.

FIG. 2 makes clear how the total division factor Q applied between lines 18 and 22 is determined by the values of the signals m_0 to n_3 .

As indicated above, the multiplier 28 determines the value required for the frequency F_1 in order to produce the correct value for F_0 having regard to the selected division factor, Q , and will now be described in detail.

As shown in FIG. 3, the multiplier 28 comprises a synchronous clock divider 126 which is connected to be controlled by the signals m_0 to n_3 presented on channel 100, and also receives 10 MHz clock pulses on a line 124. The divider 126 produces a first output on a line 128 which comprises pulses at a fixed repetition frequency of 10/800 MHz, each pulse thus defining a period, T , of $80\mu\text{s}$: these pulses are applied as one input to a five-phase clock generator 130 and also to a pulse generator 132. The divider 126 has a second output, on a line 134, comprising pulses at a frequency of $10Q/800$ MHz, where Q is determined by the values of the signals presented on the channel 100: line 134 feeds a serial dynamic BCD multiplier unit 136.

The five-phase clock generator 130 has five output lines which respectively carry signals ϕ_1 to ϕ_5 . The waveforms of the outputs ϕ_1 to ϕ_5 are shown in FIG. 5. Each output comprises a succession of negative $800\mu\text{s}$ pulses but the outputs are phase displaced with respect to each other.

The pulse generator 132 is controlled by the binary coded decimal signals received from the control panel 24 by means of the channels 90 to 96 and has four output lines 138, 140, 142, and 144 carrying signals P2, P3, P4 and P5 respectively. A signal P2 is produced on line 138 under control of the BCD signal received on channel 90. Thus, as shown in FIG. 5, the signal P2 comprises a series of positive pulses whose trailing edges are in phase with the pulses of the signal ϕ_2 but the length of each pulse of the signal P2, in multiples of $80\mu\text{s}$, is directly proportional to the value of the BCD signal on the channel 90. Thus, if the BCD value presented on channel 90 is decimal 1, then each pulse of the signal P2 will have a length of $80\mu\text{s}$ (that is, 1 times $80\mu\text{s}$). If the BCD signal on channel 90 is decimal 6, for example, then each pulse of the signal P2 will have a length of $480\mu\text{s}$ (that is, 6 times $80\mu\text{s}$ or six-tenths of the length of each pulse of the signal ϕ_2); and so on. In similar fashion, the signals P3 to P5 are controlled by the BCD signals presented on channels 92 to 96 respectively and, as shown in FIG. 5, the signals P3 to P5 respectively comprise trains of pulses whose trailing edges are in phase with the signals ϕ_3 to ϕ_5 , the lengths of the pulses being directly dependent on the BCD signals received on the corresponding channels 92 to 96.

Therefore, the serial multiplier unit 136 serially receives pulses of the signals P2 to P5, in that order.

screening and relatively high noise values. The synthesizer described and illustrated uses comparatively low frequencies which do not impose unusually difficult screening requirements or produce unacceptable noise levels (in fact, the divider 20 has the effect of reducing the noise when the division factor Q is relatively high). The synthesizer described and illustrated overcomes these disadvantages by virtue of its use of the divider 20. The provision of the indices selector 26 and the multiplier 28 ensures that the divider 20 does not render the synthesizer difficult to set up: if, for example, the indices selector 26 and the multiplier 28 were not present, and the divider 20 were made manually settable, then it would be necessary for the operator first to calculate or otherwise ascertain the correct division factor required for his desired output frequency, then to calculate the corresponding value of F_1 , and finally to set up the desired values of Q and F_1 . This would be a time consuming process, and would also suffer from the disadvantage that the value of the output frequency F_0 would not be immediately apparent from the setting of the controls of the synthesizer. These disadvantages are overcome by the provision of the indices selector 26 and the multiplier 28.

Each synthesizer block 10 to 16 may, for example, comprise a simple mixer with filtering means to select the upper sideband as the required output frequency. Instead, however, each synthesizer block may comprise a mixer which mixes one of the input frequencies with the output of a voltage controlled oscillator, and a phase sensitive detector connected to compare the lower sideband output from the mixer with the other of the two input frequencies, the phase sensitive detector being connected to control the voltage controlled oscillator in a sense such as to tend to maintain the difference between the two frequencies compared at zero.

Although the divider 20 has been indicated as dividing by a factor given by $10^m \cdot 2^n$ where m and n are variable, the divider may divide by any other suitable variable factor of different mathematical form.

In a modification, the system is fitted with a range switch which enables different possible frequency ranges for the output frequency F_0 to be selected: for example, for range setting 1, F_0 would be variable between 10 and 159.99, for range setting 2, F_0 would be variable between 1 and 15.999, and for range setting 3, F_0 would be variable between 0.1 and 1.5999. In order to achieve the desired ranges, the selection of the divide-by-10 dividers in the divider 20 would be controlled by the range switch and would not be controlled by the indices selector 26 which would only determine changes in the value of the signal n . Thus in range setting 1, the range switch would select neither of the two divide-by-10 dividers 108, 110. In setting 2, the switch would select divider 108 alone, while in setting 3 it would select both dividers 108 and 110. The multiplier 28 would only respond to changes in the signal n and would be unaffected by the range change switch.

This method of range changing is advantageous in that it reduces the multiplication factor to be employed by the multiplier 28 to a maximum of 8. Since the multiplier 28 is dynamic in operation, it takes longer to carry out multiplication at high multiplication factors than at low factors, and the range changing method described enables excessive delays to be avoided.

What I claim is:

1. A frequency synthesizing system, comprising frequency synthesizing means operative to produce an adjustable intermediate frequency, frequency dividing means connected to receive the intermediate frequency and to divide it by an adjustable division factor to produce an output frequency,

setting means operable to set up a desired value of the output frequency, and control means connected to the setting means to respond to the value of the output frequency set up thereby and also connected to the synthesizing means and the dividing means to control the values of the said intermediate frequency and of the division factor in dependence on the value of the output frequency set up, such that the value of intermediate frequency produces, when divided by the division factor of the dividing means, the desired output frequency.

2. A system according to claim 1, in which the control means comprises

selecting means operative to produce, for each desired value of the output frequency set up by the setting means, a different and predetermined first control output representing a particular value of division factor,

multiplying means connected to the setting means and the selecting means and operative to multiply the desired value of the output frequency set up by the setting means and the first control output to produce a second control output,

means feeding the first control output to the dividing means to set the division factor thereof, and means feeding the second control output to the frequency synthesizing means to set the value of the said intermediate frequency.

3. A system according to claim 2, in which the dividing means comprises means operative to divide the intermediate frequency by a division factor of X^x , where X is a fixed integer and x is an integer which is varied in dependence on the value of the first control output whereby to vary the value of the division factor.

4. A system according to claim 3, in which the dividing means comprises means for dividing the intermediate frequency by an additional factor of Y^y , where Y is a fixed integer and y is an integer which is manually variable to alter the range of the output frequency.

5. A system according to claim 2, in which the dividing means comprises means operative to divide the intermediate frequency by a division factor of $X^x \cdot Y^y$, where X and Y are fixed integers, and x and y are integers which are varied in dependence on the value of the first control output, whereby to vary the value of the division factor.

6. A system according to claim 5, in which X is 2 and Y is 10.

7. A system according to claim 1, in which the frequency synthesizing means comprises

a plurality of synthesizer arrangements each operative to synthesize a separate frequency, and summing means connected to sum the separate frequencies to produce the said intermediate frequency, each synthesizing arrangement comprising means responsive to the control means to set the value of the said separate frequency which it synthesizes

whereby that frequency determines the value of a respective one of the decades of the said intermediate frequency.

8. A system according to claim 2, in which the frequency synthesizing means comprises a plurality of synthesizer arrangements each operative to synthesize a respective individually variable frequency which is variable stepwise from a predetermined datum frequency, and summing means for summing the individually variable frequencies to produce the said intermediate frequency, 10 each synthesizer arrangement comprising means responsive to the said second control output to vary the value of the respective individually variable frequency stepwise in dependence thereon, the various datum frequencies and the step sizes in the synthesizer arrangements being selected such that the value of each individually variable frequency determines a different one of the decades of the 20 said intermediate frequency.

9. A system according to claim 2, in which the frequency synthesizing means comprises a plurality of synthesizer arrangements each operative to synthesize a separate frequency, and 25 output means connected to add these separate frequencies to produce the intermediate frequency, each synthesizer arrangement comprising means for adding two frequencies each having a 30 predetermined datum value and at least one of which is variable stepwise in predetermined steps from the datum value, and means responsive to the said second control output to vary the variable frequency, 35 the said datum value and the sizes of the step variations in the variable frequencies being such that the frequency synthesized by each synthesizer arrangement determines the value of a respective one of the decades of the said intermediate 40 frequency.

10. A system according to claim 9, in which the intermediate frequency comprises the sum of a fixed

frequency and a variable frequency, the variable frequency comprising four decades, and in which:

there are three said synthesizing arrangements, the first synthesizer arrangement is connected to add a first fixed frequency fixed at a predetermined value and a first variable frequency variable in predetermined steps from a predetermined datum value, and includes means responsive to the said second control output to vary the value of the first variable frequency stepwise whereby to produce a first synthesized frequency, the second synthesizer arrangement is connected to add the said first synthesized frequency and a second variable frequency which is variable in predetermined steps from a predetermined datum value, and includes means responsive to the said second control output to vary the value of the second variable frequency stepwise whereby to produce a second synthesized frequency, the third synthesizer arrangement is connected to add third and fourth variable frequencies variable in predetermined steps from respective predetermined datum values, and includes means responsive to the said second control output to vary the values of the third and fourth variable frequencies stepwise whereby to produce a third synthesized frequency, the said output summing means is connected to receive and sum the said second and third synthesized frequencies whereby to produce the said intermediate frequency, the datum values of the first fixed frequency and of the first, second, third and fourth variable frequencies and the sizes of the predetermined steps of the latter frequencies are such that the first variable frequency is variable to vary the value of the least significant decade in the said intermediate frequency, the second variable frequency is variable to vary the value of the next more significant decade thereof, and the third and fourth variable frequencies are respectively variable to vary the values of the two most significant decades thereof.
